IGNITION AND PRODUCTION OF CARBONACEOUS STRATA

Carl J. Helmers, Bartlesville, Okla., assignor to Phillips Petroleum Company, a corporation of Delaware
No Drawing. Filed Dec. 29, 1958, Ser. No. 783,206
10 Claims. (Cl. 166—11)

This invention relates to an improved process for initiating in situ combustion in a carbonaceous stratum and producing the same by inverse injection of combustion-supporting gas.

In situ combustion in the recovery of hydrocarbons from underground strata containing carbonaceous material is becoming more prevalent in the petroleum industry. In this technique of production, combustion is initiated in the carbonaceous stratum and the resulting combustion zone is caused to move thru the stratum by either inverse or direct air drive whereby the heat of combustion of a substantial proportion of the hydrocarbon in the stratum drives out and usually upgrades a substantial proportion of the unburned hydrocarbon material.

In the inverse air injection process upgrading of hydrocarbons by thermal and catalytic cracking is effected by driving the produced hydrocarbon material thru the hot rock or sand between the inversely traveling combustion front and the production borehole.

The ignition of carbonaceous material in a stratum around a borehole therein followed by injection of air thru the ignition borehole and recovery of product hydrocarbons and combustion gas thru another borehole in the stratum is a direct air drive process for effecting in situ combustion and recovery of hydrocarbons from the stratum. In this type of operation the stratum usually plugs in front of the combustion zone because a heavy viscous liquid bank of hydrocarbon collects in the stratum in advance of the combustion zone which prevents movement of air to the combustion process. To overcome this difficulty and to permit the continued progress of the combustion zone thru the stratum, inverse air injection has been resorted to. By this technique, a combustion zone is established around an ignition borehole by any suitable means and air is fed thru the stratum to the combustion zone from one or more surrounding boreholes.

In situ combustion techniques are being applied to tar sands, shale, Athabasca sand and other strata in virgin state, to coal veins by fracturing, and to strata partially depleted by primary and even secondary and tertiary recovery methods.

A problem in establishing in situ combustion, particularly, by inverse air injection, lies in the difficulty of igniting a carbonaceous stratum containing producible hydrocarbons and propagating the resulting combustion zone thru the stratum without the fire being extinguished. If the stratum contains a high percentage of heavy hydrocarbon material, such as in a tar sand, igniting by direct injection of air thru the ignition borehole with application of heat thereto by any conventional means risks the plugging of the stratum by driving the liquefied semi-solid and solid hydrocarbon deposit thru the stratum away from the borehole where it is cooled and congeals. While ignition by direct injection thru the heated borehole is much more effective in igniting a carbonaceous stratum the risk of plugging off the stratum and extinguishing of the fire front in many applications of the in situ combustion process is too great and is to be avoided. On the other hand it has been found extremely difficult to ignite the stratum adjacent an ignition borehole by passing inversely injected air thru the stratum into the hot ignition borehole from one or more offset boreholes.

Another problem in the recovery of hydrocarbons from

2

a carbonaceous deposit in a sand or rock stratum by inverse air injection comprises disintegration of the sand structure around the production borehole thru which the hot combustion gases and produced hydrocarbons pass in an inverse burning process. The sand or spalled rock fills up the borehole and/or is produced or entrained in the produced gases, thereby increasing the problem of separation and recovery of hydrocarbon material from the effluent gas stream.

10 This invention is directed to a process for igniting a carbonaceous stratum and producing hydrocarbons therefrom by inverse air injection which overcomes the problems set forth in the preceding paragraphs.

Accordingly, it is an object of the invention to provide 15 a process for igniting a carbonaceous stratum by injecting combustion supporting gas thru the stratum into an ignition borehole. Another object is to simultaneously ignite a carbonaceous stratum around a borehole therein and begin the movement of the resulting combustion or 20 fire front thru the stratum by counterflow injection of combustion supporting gas without resorting to direct injection thru the ignition borehole and without reversing the direction of flow of said gas. A further object is to provide an improved method or process of initiating 25 counter-flow in situ combustion which is fast, simple, and certain. It is also an object of the invention to prevent borehole caving and plugging and entrainment of sand and spalled rock in an inverse in situ combustion process. Other objects will become apparent upon consideration of the accompanying disclosure.

A broad aspect of the invention comprises loosely packing coarse aggregates of porous refractory material in an ignition borehole within a carbonaceous stratum, the porous material being soaked or saturated with a heavy 35 liquid hydrocarbon fuel either before introduction into the borehole or thereafter by any suitable means, igniting the fuel in the packed mass and burning the same by inverse injection of combustion supporting gas thru the stratum into the borehole so that the combustion in the 40 fuel pack expands throughout the same and ignites the adjacent carbonaceous stratum and establishes a fire front therein which moves away from the ignition borehole countercurrently to the flow of combustion-supporting gas. In this manner the inverse in situ combustion process is initiated and can be continued by merely continuously injecting combustion supporting gas into the stratum thru one or more offset injection boreholes therein. The process is applicable to any of the conventional well 45 patterns, such as the 5, 7, or 9-spot pattern in which a ring of injection boreholes surrounds a central ignition and production borehole, or the line drive process in which a combustion or fire front is moved away from a ring of ignition and production boreholes to a parallel line of 50 injection boreholes on either or both sides of the line of ignition boreholes.

The simplest method of igniting the fuel pack in the ignition borehole comprises dropping a fusee or other incendiary device down the borehole onto the top of the 55 pack and injecting combustion supporting gas thru the stratum into the pack and up through the borehole so that a combustion zone or fire front is established in the top of the fuel pack and is caused to migrate downwardly therethrough and also into the carbonaceous stratum contiguous to the fuel pack, thereby initiating the in situ combustion of the stratum.

It is also feasible to pack the saturated refractory material around an axial perforate pipe or tubing which is imperforate above the pack so that ignition of the fuel 70 pack can be effected at the center or axis thereof and the combustion zone can then be advanced radially outwardly to contact the stratum at the borehole wall simultaneously

at substantially all points along the stratum. In utilizing this method, the perforate pipe must either be fabricated of refractory ceramic material or of an alloy which stands extremely high temperatures. Another method of igniting the fuel pack axially thereof from top to bottom is to suspend an incendiary device in the form of a rope or cylinder axially within the borehole opposite the stratum and pack the fuel around the incendiary material so that by passing combustion supporting gas thru the stratum into the fuel pack and igniting the incendiary material the same burns as a fuse throughout the length of the pack and ignites the fuel which is in contact with the combustion supporting gas stream.

It has been found that with certain types of fuel the combustion zone cannot be moved through the fuel pack by countercurrent injection of air alone. In order for the fire front to be moved through the fuel pack by inverse air injection as the combustion-supporting gas, the fuel must be a heavy liquid hydrocarbon fuel which contains a substantial proportion of hydrocarbons boiling below the ignition temperature of the fuel in the well bore, which is about 500° F. To illustrate, either asphalt or diesel fuel, alone, does not permit inverse propagation of the combustion front thru the fuel pack using inverse air, alone, but a mixture of these fuel components in the proportion of 40 to 60 volume percent of diesel fuel and 60 to 40 percent of asphalt permits easy propagation of the combustion front thru the pack countercurrently to injected air. Air alone is successful in moving the combustion front thru the fuel pack if the heavy hydrocarbon fuel contains about 3 to 5 percent of volatile material boiling below about 500° F.

However, it is feasible to ignite a fuel pack containing diesel oil or other heavy liquid hydrocarbon of wide boiling range either at the top of the pack or axially thereof and move the resulting combustion front thru the pack into the stratum by admixing with the injected air a suitable hydrocarbon fuel, such as propane or liquefied petroleum gases, in a concentration of about 1 to 3 or 4 volume percent. Since it is difficult in some strata to establish a combustion front around an ignition borehole with inversely injected air, alone, the incorporation of fuel gas in the combustion-supporting gas also facilitates establishing the combustion front in the stratum and moving the same therethrough countercurrently to the injected gas. It has also been found that incorporation of about 1 to 2 or 3 volume percent of fuel gas (propane) in the injected air in an inverse in situ combustion process materially increases the rate of movement of the front through the stratum and also materially increases the amount of hydrocarbons produced in the process. It is therefore highly advantageous to inject with the inverse air a small concentration of fuel gas in that it assists in movement of the combustion zone both thru the fuel pack and through the stratum and assures the advantages of faster, as well as increased, recovery of hydrocarbons.

When utilizing a mixture of diesel oil and asphalt in a fuel pack comprising porous alumina fire brick coarsely ground to about one-half inch diameter pieces, propagation of the combustion front could be effected utilizing air velocities in the range of about 1270 to 2950 feet per hour. This range of air velocity was found by packing the coarse fire brick saturated with a mixture of equal parts of diesel oil and asphalt (1.0362 specific gravity and 53 penetration) into a 1 1/8-inch Vycor tube and igniting one end while passing air through the tube from the other end. It was in this manner that it was found that a fire front or combustion zone could not be propagated thru the fuel pack countercurrently to the air stream utilizing diesel oil, alone, no doubt because of the too volatile nature of the diesel oil. It was also found that where the fuel in the pack was a mixture of paraffin wax and carbon black, propagation could not be effected by air, alone, probably because the fuel in the pack was not volatile enough.

Two successful field tests were made in a tar sand lying about 50 to about 75 feet below ground. In the first test a virgin ignition well bore was packed with coarse fragments of porous alumina fire brick saturated with a 5 50—50 solution of asphalt in diesel fuel and ignited by means of a fusee dropped down the casing. Propane-air premix containing from 1 to 3 percent by volume of propane was then injected into two offset in-line walls. In this manner a counterflow combustion front was established in the tar sand and sustained for about two days at which time the burning was intentionally terminated by stopping air injection.

The second test involved the re-ignition of the same zone in which the combustion had just been extinguished. 15 After the original ignition well had been cooled by water injection, three gallons of diesel fuel were added and the well was shut in to allow the liquid to penetrate through the alumina-packed well bore. The well was again ignited with a fusee, and propane-air premix injection was resumed at the offset wells. A counterflow combustion zone, feeding on injected fuel alone, was re-established in the formation without difficulty. The new front appeared to travel outward more rapidly from the ignition well than the original front, probably because of the preheated rock 20 which it encountered.

Any porous ceramic refractory material in coarse particulate form may be used in the process. Such materials as alumina, silica-alumina, mullite, silica (alone) and other highly refractory minerals in the form of porous 25 aggregates are operable in the fuel pack.

In application of the process to thick strata, it may be advantageous to utilize a fuel pack which does not completely fill the borehole within the stratum to be ignited and produced. Where the pressure drop thru the fuel 30 pack is undesirably large the packing of the borehole only part way up to the top of the stratum, such as in the range of 1/3 to 2/3 of the depth or thickness of the stratum, reduces the pressure drop and at the same time is effective in preventing spalling and caving of the sides 35 of the borehole in the packed area, while spalling which occurs above the pack does not plug the borehole or increase the pressure drop thru the pack because the velocity of the produced gases above the fuel pack entrains these particles of sand and rock. The depth of the fuel pack 40 in relation to the stratum will depend upon the permeability profile of the stratum, the well diameter, and the maximum size of particles to be entrained out of the well. These factors allow calculation of the portion of the well to be filled with the refractory fuel pack. This 45 embodiment of the invention does not entirely prevent production of sand and debris but it does prevent gradual accumulation of sand and plugging of the bottom of the well. Since sand production is usually a major problem only in the early stages of combustion this aspect of the 50 invention is a satisfactory method of ignition which does prevent plugging of the well with debris.

Certain modifications of the invention will become apparent to those skilled in the art and the illustrative details disclosed are not to be construed as imposing unnecessary limitations on the invention.

I claim:

1. A process for igniting a carbonaceous stratum adjacent an ignition borehole therein and reducing borehole caving and spalling while producing hydrocarbons 60 therefrom, which comprises positioning in said borehole a mass of porous refractory solids saturated with a heavy liquid fuel; burning said liquid fuel in said ignition borehole by igniting same and passing combustion-supporting gas consisting essentially of a mixture of air and fuel gas, said fuel gas being in the range of 1 to 3 volume percent of the mixture thru said stratum to said ignition borehole from at least one offset injection borehole, thereby igniting said stratum and establishing a fire front 65 therein; thereafter continuing the injection of said gas so as to advance the resulting fire front thru said stratum 70

countercurrently to the flow of said gas; and recovering thru said ignition borehole hydrocarbons produced by the combustion.

2. The process of claim 1 wherein said liquid fuel comprises diesel fuel.

3. The process of claim 1 wherein said mass of solids is coextensive vertically with said stratum.

4. The process of claim 1 wherein said mass of solids extends from the bottom of said ignition borehole a distance in the range of $\frac{1}{3}$ to $\frac{2}{3}$ of the thickness of said stratum.

5. The process of claim 1 wherein said heavy liquid fuel is a wide boiling range hydrocarbon of which 3 to 5% by volume boils below about 500° F.

6. The process of claim 1 wherein said fuel gas is propane.

7. The process of claim 1 wherein said stratum is a tar sand and same is produced by inversely injecting about 1 to 3 volume percent of fuel gas with air.

8. The process of claim 2 wherein said liquid fuel also contains asphalt in the range of 40 to 60 weight percent of said liquid fuel.

9. A process for re-igniting a carbonaceous stratum thru a first borehole from which a fire front has been moved into said stratum toward a second borehole therein so as to leave a denuded burned out area between said fire front and said first borehole and wherein the temperature at said fire front has fallen below a com-

bustion-supporting level so that combustion is terminated, which comprises igniting and burning in said first borehole a heavy liquid hydrocarbon fuel absorbed in a mass of porous refractory solids by feeding combustion-supporting gas thereto to heat said borehole to ignition temperature of the hereinafter defined mixture; passing a combustible mixture of fuel gas and air in which said fuel gas is in the range of 1 to 3 volume percent from said injection borehole thru said stratum and the former fire front to said production borehole so as to establish a combustion zone in the wall of said production borehole; and continuing the injection of said mixture as move said hot combustion zone thru the denuded stratum to the locus of said former fire front and into the unburned stratum so as to reignite the carbonaceous material in said stratum and re-establish the fire front therein.

10. The process of claim 9 wherein said liquid fuel is ignited at the top of said mass and the resulting combustion zone is moved downwardly thru said mass.
